UNITED STATES PATENT OFFICE.

EDWARD HAEUSSNER, OF ST. LOUIS, MISSOURI.

SPIKE.

1,113,004.

Specification of Letters Patent.

Patented Oct. 6, 1914.

Application filed March 31, 1914. Serial No. 828,576.

To all whom it may concern:

Be it known that I, EDWARD HAEUSSNER, a citizen of the United States, residing at St. Louis, in the State of Missouri, have invented new and useful Improvements in Spikes, of which the following is a specification.

The present invention relates to improvements in construction spikes, the object being to provide a spike which may be easily driven within a timber to separate the grain of the wood in such a manner that the same will bear forcibly upon the spike to prevent the removal of the same.

Another object of the invention is to construct a spike which will be sustained in position, when driven home, in such a manner as to prevent its accidental removal, but which may be rotated to bring its head out of engagement with a plate, such as the base flanges of a rail, to permit of the removal of the plate or rail without the necessity of removing the spike.

With the above and other objects in view, the improvement resides in the construction, combination and arrangement of parts set forth in the following specification and falling within the scope of the appended claims.

In the drawing: Figure 1 is a sectional view through a timber, such as a wooden tie, illustrating the spike driven therein and engaging with the base flange of a rail. Fig. 2 is a similar view showing the spike rotated to bring its head out of engagement with the plate or the base flange of the rail, and Fig. 3 is a perspective view of the spike.

Referring now to the drawing in detail, the numeral 1 designates a timber, which, in the illustration, is in the nature of a tie or sleeper, and 2 a plate which is secured to the timber, the plate being shown in the nature of a base flange of a rail.

3 designates my improved spike. This spike includes a round shank 4, and an elongated substantially rectangular head 5. The under-face of the head is inclined so that the same will effectively rest upon the base flange of the rail, and the engaging portion of the head 50 projects beyond the shank for a greater distance than the remainder of the head. The shank 4 is substantially cone-shaped, that is, its end is of a materially smaller size than the portion thereof which is connected or formed with the head 5. Formed upon

the periphery of the substantially cone-shaped shank is a spiral enlargement 6, the lower portion of which terminates in a point 7 which is arranged centrally of and which extends a suitable distance beyond the reduced lower end of the shank. The shank, at a suitable distance above the end provided with the point 7 is integrally formed with a lug member 8, the same having its upper portion or base horizontally straight and extending laterally from the spike in a direction transverse to that of the side walls of the substantially rectangular head 5. The lug 8, from its opposite ends, is beveled to its connection with the shank proper, as indicated by the numerals 9—9, and the corners of the substantially key-shaped lugs are preferably rounded, the spiral enlargement 6 below the said lug ending with one of the rounded corners. The shank 4 is provided with a second lug 10 which is arranged a suitable distance above the lug 8, and this lug is also substantially key-stone shaped in side elevation, the sides of the said lug being of a width equaling the width of the shank but the head of the lug extends a suitable distance beyond the opposite sides of the shank and terminates in downwardly beveled walls 11—11, the corners of the said ends being preferably rounded and the spiral 6 between the lugs 8 and 10 preferably terminating with one of the said rounded corners of the lug 10. The lugs 8 and 10 are arranged above the shank preferably at right angles to each other, as illustrated.

The point 7 permits of the spike being positioned upon the timber 1, and an impact of face, such as the blows of a hammer upon the head, will force the shank of the spike within the timber, separating the grain of the timber, and causing the said separated grain to forcibly contact between the spirals and against the sides and over the tops of the lugs, to effectively retain the spike when driven home upon the timber. The spiral arrangement of the shank permits of the same being turned or rotated to a certain extent without interfering with the holding or retaining propensity of the spike, when an instrument, such as a wrench, engages with the head of the spike so that the said spike may be rotated to bring its head out of engagement with the plate 2 to permit of the same being removed if desired.

Having thus described the invention, what I claim is:

1. A spike having a cone-shaped shank and an elongated head and a rectangular head, the shank having a spiral enlargement and being formed with oppositely extending key-stone shaped lugs which interrupt the said spiral enlargement.
2. A spike including a shank and a rectangular head having the engaging portion thereof extending beyond the shank for a greater distance than the remainder of the head, the shank being cone-shaped and being integrally formed with a spiral enlargement which, at the reduced end of the spike, terminates in a point which projects cen-

trally from the said end of the shank, the shank being formed with laterally extending lugs, one arranged at a right angle to the other, the sides of the lugs being disposed at an angle similar to the angular sides of the shank, the corners of the lugs being rounded, and the spiral enlargements communicating with one of the rounded corners of the lug. 25

In testimony whereof I affix my signature in presence of two witnesses.

EDWARD HAEUSSNER.
